UNITED STATES PATENT OFFICE.

ARTHUR F. CASE, OF CLEVELAND, OHIO, ASSIGNOR TO THE WELLMAN-SEAVIER-MORGAN COMPANY, OF CLEVELAND, OHIO, A CORPORATION OF OHIO.

LIFTING CAR DUMPER.

Application filed August 18, 1922. Serial No. 582,596.

To all whom it may concern:

Be it known that I, ARTHUR F. CASE, a citizen of the United States, residing at Cleveland, in the county of Cuyahoga and State of Ohio, have invented a certain new and useful Improvement in Lifting Car Dumper, of which the following is a full, clear, and exact description.

This invention relates to improvements in car dumper and particularly of the lifting type. A dumper of this type has a frame or cradle-supporting structure and a cradle which is adapted to receive a car and then to be elevated to a predetermined height and turned laterally to dump the contents of the car into a suitable receiving element such as a pan designed to discharge into a boat or other receiving member.

In dumper of this type, when the cradle is lifted to the point where the turning is to take place, a pair of pivot members at the upper corners of the cradle engage a pair of co-operating pivot members constituting the axis about which a cradle is turned. These co-operating pivot members may be fixed in the frame but usually they are carried by a girder adjustable vertically on the front side of the frame in order that the height of the dumping point may be varied.

With this construction the cradle is supported by the pivot members at its two ends only, a third or intermediate set of pivot members between the ends of the cradle being in practice impossible of use for the reason that due to the bending load on the cradle created by the car with its contents, it would be extremely unlikely that more than two of the pivot members carried by the cradle would simultaneously engage the co-operating pivot members carried by the frame. Furthermore, since the pivot members on the cradle and frame move into and out of engagement with each other, i. e. are not fastened together in fixed relation, cushioning means for checking the upward movement of the cradle before the pivot members move into engagement is not practicable and the cradle must be brought practically to a dead stop when its pivot members are caused to engage the pivot members of the frame.

The above construction is satisfactory to an extent for cars of ordinary size but not

only are the cars used in handling coal increasing in size, but with certain installations the requirements are such as to make highly desirable the dumping of two cars at one time. The extreme length of a cradle which is required in handling two cars at one time renders difficult the supporting of the cradle at its ends only, particularly while being turned, and necessitates a very massive cradle to withstand the weight and bending stresses.

The principal object of the invention is to provide a construction which will admit of the cradle being supported intermediate as well as at its ends, both while being elevated and turned, and which is therefore admirably adapted for handling heavy loads and two cars at one time.

Further, the invention aims to provide a construction wherein the rate at which the cars are being handled can be increased by eliminating the necessity for bringing the cradle to a stop or to substantially a stop near the end of the upward movement of the cradle as has been required heretofore.

In accordance with my invention, I eliminate separable pivot members which move into engagement at the end of the upward movement of the cradle and move out of engagement at the start of the lowering movement after the cradle has been turned back to normal position. On the other hand, pivot members having a fixed relation are employed, like the members of an ordinary hinge or series of hinges. This is accomplished in the preferred construction by hinging the cradle to a cross girder which is designed to move up and down with the cradle on guideways on the front side of the dumper frame. The hoisting and counterweight cables are connected to the girder instead of to the cradle as heretofore, and stop members are provided along the guideways adapted to be engaged by the ends of the girder when the cradle has been elevated to the desired height and when the upward movement of the girder is stopped the continued pull on the hoisting cables turns the cradle with reference to the girder so as to dump the car or cars thereon.

The use of a girder which travels up and down in the dumper frame and to which the cradle is hinged or pivoted enables me to support the cradle by pivot or hinge mem-

bers at a number of points along its length and in practice, at least three of these hing-
ing members are utilized, two at the ends
of the cradle and one midway between its
ends.

The stop members which the ends of the
girder are designed to engage may be of
the fixed or non-adjustable type if the height
to which the cradle is elevated before being
turned is not required to be varied, or they
may be adjustable up and down along the
corner posts of the dumper frame. Fur-
thermore, I prefer to use stop members
which cushion the upward movement of the
girder and avoid material shock when the
girder reaches the end of its travel and at
the same time allow greater speed in oper-
ating the dumper by eliminating the neces-
sity of slowing down the movement of the
dumper to nearly a dead stop near the end
of the upward movement.

Further advantages which will be pointed
out in the specification are attained by my
invention which may be here briefly sum-
marized as consisting in certain novel de-
tails of construction and combinations of
parts which will be described in the speci-
fication and the accompanying set of claims.

In the accompanying sheets of drawings,
Fig. 1 is an end view of a dumper embodying
my invention, the parts being shown some-
what conventionally; Fig. 2 is a similar view
of the cradle removed from the frame and
showing also conventionally the hoisting and
counterweight cables; Fig. 3 is a view look-
ing toward the front or dumping side of the
dumper, the cradle with its girder being
shown by full lines in the lowermost position
and the girder being shown also by dotted
lines in elevated position; Fig. 4 is a
detail sectional view on an enlarged scale
substantially along the line 4—4 of Fig. 3;
Fig. 5 is a fragmentary elevation with parts
in section showing one end of the girder
and a portion of the end post of the frame;
Fig. 6 is a sectional view substantially along
the line 6—6 of Fig. 5; Figs. 7 and 8 are en-
larged detail views in side and end elevation
respectively of the spring buffers with
which the ends of the girder engage at the
end of the upward movement of the girder
and cradle, parts being in section; and Fig.
9 is a sectional plan view along the line 9—9
of Fig. 3, the parts being shown on an en-
larged scale.

Referring now to the drawings, 10 repre-
sents the frame of the car dumper, which
frame as is usually the case, is formed of
suitable structural material and is provided
on the front or dumping side which is the
left-hand side of Fig. 1, with end posts 11,
(see Figs. 3 and 4) on the inner sides of
which are formed cradle guideways 11^a.

The cradle which is shown at 12 is L-
shaped as usual, being provided with an up-

right front portion 12^a and a base portion
12^b, the latter having a platen with rails 13
to receive the car or cars to be dumped.

In accordance with the present invention
the cradle is provided with a girder 14 ex-
tending across the front side 12^a, which
girder is guided for vertical movement in
the guides 11^a of the corner posts 11. Prefer-
ably each end of the girder is provided
with side thrust rollers 15 and with at least
one end thrust roller 16 which are best
shown in Figs. 5 and 6, and engage the side
and inner walls of the guideways 11^a.

The cradle 12 is hinged to the girder at
and intermediate its ends. Preferably it
is hinged or pivoted at three points, located
respectively at the ends and midway be-
tween the ends of the girder and cradle. The
hinges are so located that the cradle may be
swung or turned upwardly and outwardly
over the top of the girder as shown by dotted
lines in Fig. 1, and though the hinge
members may be formed in different ways,
in this instance each consists of a hinge pin
17 secured to the top of the girder and a
bearing 18 secured to the front side 12^a of
the cradle and through which the pin ex-
tends.

Usually lifting cables and counterweight
cables are connected to the ends of the
cradle, the counterweight cables being con-
nected to the ends of the front portion of
the cradle, and the lifting cables being also
connected to the front portions of the cradle
and passing down around beneath the cradle
so that when the lifting cradles are wound
on the operating drums, the cradle will first
be elevated in the frame or tower of the
dumper and then turned or rotated about
the pivot members of the frame after they
have been engaged by the pivot members
of the cradle. Since the cradle is both
moved vertically and turned, it is unneces-
sary that the cables be connected to the
front part of the cradle by bearings which
permit the turning movement. This detail
is unsatisfactory and is not necessary when
the lifting girder 14 is employed, as both
the lifting cables which are shown at 19 and
the counterweight cables which are shown at
20 are connected direct to the girder 14, these
cables being attached to fixed anchorages
21^a and 22^a, (see Fig. 5) carried by the girder
and being always in the same directional re-
lation to the girder. This is a decided ad-
vantage over the anchorages necessitated
when the cables are connected to the cradle
itself.

Though the details or specific arrange-
ments of the cables and their sheaves are im-
material to the present invention, it may be
stated that the lifting cables 19 pass about
sheaves 21 which are located at the top of
the frame, one part of each cable 19 passing
about the under side of the cradle as is

customary. In this instance each of the cables 19 passes about the sheave of a carriage 22, the lower sheave of which is engaged by a cable 23 fixed at one end and 5 passing about the winding drum 24. The counterweight cables 20 pass about sheaves 25 at the top of the frame and are connected to counterweights 26. Additionally, car clamp cables, the function of which is to 10 hold the car on the cradle while the latter is being turned, will be provided, but these are not shown as they do not directly involve the invention and may be arranged in any of the customary ways.

15 As already stated, it is possible with the present arrangement to provide spring stops or buffers at the upper cradle position. This very much facilitates the slowdown which is one of the chief difficulties in lifting car 20 dumpers as now made. The dumping hooks or separable pivot members now employed do not permit of such a spring stop arrangement and unless the cradle is brought to almost a dead stop the structure is subjected 25 to a severe shock when the pivot members move into engagement. This is entirely avoided by my improved construction which eliminates the necessity of a careful slowing down of the lifting or turning cables at the 30 time that the vertical movement ceases and the turning movement of the cradle begins.

In the construction shown, the spring buffers are designated at 27, these being supported on the inner sides of the corner posts 35 11 so as to be engaged by the ends of the girder. As already stated, these spring buffers which stop the upward movement of the cradle may be supported in a fixed position on the corner posts, or if the height 40 of the dumping point is to be varied as is sometimes the case, they may be made adjustable along the posts. In this instance each spring stop or buffer includes a housing 28 containing vertically disposed springs 29, surrounding bolts 30, at the bottom of 45 which is a buffer block 31 which is adapted to be engaged and lifted against the yielding opposition of the springs 29 by a block 32 on the end of the girder 14. The buffer block 31 is enclosed in a cap 33 with projecting flanges 33^a which are adapted after 50 a predetermined vertical movement during which the springs 29 are compressed to engage the bottom of the spring stop housing 28, the latter constituting a fixed stop which definitely positions the girder while the turning movement is taking place.

55 Thus it will be seen that after the cradle receives one or more cars with the cradle in its lowermost position, the cradle and its girder, to which the cradle is pivoted, travels vertically, with the ends of the girder guided in the frame through the medium of the side and end thrust rollers with which 60 the ends of the girder are provided, and

when the girder is near the upper end of its vertical movement the blocks 32 engage the buffer blocks 31, checking the upward movement of the girder and allowing it to come to a complete stop with very little if any 70 shock. This allows a more rapid operation of the dumper inasmuch as it eliminates the necessity of a very substantial and carefully controlled slow down. As soon as the vertical movement of the girder is stopped, the 75 continued pull of the lifting cables causes the cradle to be turned on its pivoted axis with the girder until full dumping position is reached and the contents dumped from the car or cars, after which the cradle is turned back to normal position and with the girder is lowered to its loading position. The fact that it is unnecessary to guide the cradle itself in the guideways of the frame, and the fact that the guided part, namely, 80 the girder, moves vertically only in the frame, causes the arrangement to lend itself to a desirable installation of guide rollers which would be difficult to apply to lifting dumpers as at present constructed. 85

90 Additionally by having the lifting and counterweight cables connected to the girder instead of to the turning cradle as in prior constructions, the cable anchorages are fixed and are therefore far more satisfactory than those which are used at present and which are so made to permit the turning movement.

95 More important still, however, is the fact that with the present arrangement wherein the cradle is pivoted or hinged to the girder by hinged members which are always in engagement, I am enabled to introduce a center support for the cradle, or if desired, 100 a number of supports between the end supports, thus reducing the span which is necessary to take the vertical bending movement caused by the car and its contents and adapting the cradle for unusually heavy loads or for dumping two or possibly 105 even more than two cars at a time.

110 While I have shown the preferred construction only, I do not desire to be confined to the precise details or arrangements shown, but aim in my claims to cover all 115 such modifications which do not involve a departure from the spirit and scope of my invention in its broadest aspects.

Having described my invention, I claim:

1. In a lifting car dumper, a frame, a 120 cradle having a portion adapted to receive a car and an upwardly extending side portion, means for moving the cradle upwardly in the frame and then turning the same to dump the contents of the car, and means for pivotally supporting the cradle during turning movement at and intermediate its ends along said upwardly extending side portion.

125 2. In a lifting car dumper, a frame, a cradle having a portion adapted to receive 130

a car and an upwardly extending side portion, means for moving the cradle upwardly in the frame and then turning the same to dump the contents of the car, and means 5 for pivotally supporting the cradle during turning movement at its ends and at its center along the upper part of said side portion.

3. In a lifting car dumper, a frame, a 10 cradle adapted to receive a car and to be elevated in the frame and then turned to dump the contents of the car, and a member extending lengthwise of the cradle at one side thereof and movable vertically with 15 the cradle to which the cradle is connected for turning movement.

4. In a lifting car dumper, a frame and cradle adapted to receive a car, and to be first elevated in the frame and then turned 20 to dump the contents of the car, and a cradle supporting member positioned along one side of the cradle, said member extending across the frame and at its ends guided therein, the cradle being pivoted to said 25 member.

5. In a lifting car dumper, a frame and cradle adapted to receive a car, and to be first elevated in the frame and then turned to dump the contents of the car, and a cradle 30 supporting member positioned along one side of the cradle, said member extending across the frame and at its ends guided therein, the cradle being pivoted to said member at and intermediate its ends.

35 6. In a lifting car dumper, a frame, a cradle adapted to receive a car and to be first elevated in the frame and then turned to dump the contents of the car, and a girder extending lengthwise of the cradle at one 40 side thereof and movable vertically with the cradle, said girder being guided by the frame and having the cradle pivoted thereto.

7. In a lifting car dumper, a frame, a 45 cradle adapted to receive a car and to be first elevated in the frame and then turned to dump the contents of the car, and a girder movable vertically with the cradle, said girder being guided by the frame and having the cradle pivoted thereto at and intermediate its ends.

50 8. In a lifting car dumper, a frame, a girder extending across the dumping side of the frame and guided by the frame for vertical movement, a cradle having an upwardly extending side portion pivoted to

the girder and movable vertically with the girder and tiltable relative thereto to dump the contents of the car, and lifting cables connected to the girder.

9. In a lifting car dumper, a frame, a 60 girder extending across the dumping side of the frame and guided by the frame for vertical movement, a cradle pivoted to the girder and movable vertically with the girder and tiltable relative thereto to dump 65 the contents of the car, and cables connected to the girder and to the cradle, means for operating the cables to first lift the girder and cradle simultaneously and then turn the cradle relative to the girder.

70 10. In a car dumper of the lifting type, a frame, a supporting member adapted to be moved vertically in the frame, a cradle pivoted to the supporting member, and means adapted to engage the supporting member for yieldingly checking the vertical movement of the cradle.

75 11. In a car dumper having guide posts and cushioning cradle stops, a cradle adapted to receive a car and adapted to be moved vertically until the cushioning stops are engaged and then to be turned to dump the contents of the car.

80 12. In a car dumper, a frame, a girder movable vertically in the frame, a cradle pivoted to the girder, means for lifting the girder and cradle and for then turning the cradle, and yieldable stops carried by the frame for limiting the vertical movement 85 of the girder.

90 13. In a car dumper, a frame having corner posts with guideways, a girder having side and end thrust rollers engaging the guideways, a cradle pivoted to the girder, and means for first elevating the girder and 95 cradle and for then turning the cradle relative to the girder.

14. In a lifting car dumper a frame having end posts provided with vertical guideways, a girder movable vertically in said 100 guideways, stops in the frame having spring bumpers for limiting the upward movement of the girder, a cradle connected to the girder, and means for elevating the girder and cradle and for turning the cradle 105 after the stops are engaged by the girder.

In testimony whereof, I hercunto affix my signature.

ARTHUR F. CASE.
